UNITED STATES PATENT OFFICE.

JESSE A. FIELD, DECEASED, BY JAMES POWELL, ADMINISTRATOR, OF DUNKIRK, NEW YORK, ASSIGNOR TO MELLIE E. FIELD, OF CLEVELAND, OHIO.

MOLDING-MACHINE.

1,287,937.

Specification of Letters Patent. Patented Dec. 17, 1918.

Application filed December 30, 1914. Serial No. 879,667.

To all whom it may concern:

Be it known that I, JAMES POWELL, a citizen of the United States, residing at Dunkirk, in the county of Chautauqua and State 5 of New York, do make known that JESSE A. FIELD, late a citizen of the United States, invented a certain new and useful Improvement in Molding-Machines, of which the following is a full, clear, and exact description.

10 This invention relates to molding machines, and is particularly adapted to compact the sand in large shallow molds, such as are prepared for radiator castings. The machine embodies as salient features a presser 15 device which progressively engages and compacts the sand in different parts of the flask, and which presser device is intermittently and automatically advanced into the flask at the end of each operation of the 20 presser device until the desired degree of packing of the sand is obtained, at which time the presser device will be returned to its starting position ready to operate upon another mold.

25 The machine further embodies features for automatically raising the sprue former as the mold is removed from the machine, and also for advancing the whole machine along the floor toward the sand pile as the machine is used.

30 Additional features of the machine will appear more in detail in the following specification.

Reference should be had to the accompanying drawings forming a part of this specification, in which Figure 1 is a side elevation of the machine; Fig. 2 is a central longitudinal vertical sectional elevation of the machine; Fig. 3 is a top plan view of the machine; Fig. 4 is an end elevation of the machine; Fig. 5 is a sectional elevation transversely of the machine; Fig. 6 is a sectional elevation showing parts of the machine in a certain operative 45 position; Fig. 7 is a view similar to Fig. 6 showing the machine in a different operative position; Fig. 8 is a side elevation of a cam forming part of the machine; Fig. 9 is a transverse sectional elevation of the 50 machine, and more particularly showing a mechanism for elevating a screw former.

The various parts of the machine are mounted upon a suitable frame comprising

lower longitudinal members 1 and 2 and upper longitudinal members 3 and 4. The 55 members 1 and 2 are, adjacent their opposite ends, secured to upright members 5 and 6 and 7 and 8. There are also transversely extending spacing members 9, 10, 11 and 12.

A supplementary presser roller frame, 60 which may be generally designated at 13 is mounted between the upright end members 5, 6, 7 and 8 bearing against these members, by which it is guided in its movement.

This frame comprises longitudinally extending lower members 14 and 15 and longitudinally extending upper members 16 and 17. The upper and lower members at points adjacent their ends are held in spaced relationship by transversely extending rods or 70 members 19, 20, 21 and 22.

The members 14, 15, 16 and 17 extend beyond the upright ends 5, 6, 7 and 8 of the frame, and at their extending portions there are upright members 23 and 24 which join 75 the longitudinally extending members 14 and 16, and there are similar upright members 25 and 26 which join the longitudinally extending members 15 and 17 of the frame 13.

The members 23 and 24 are adapted to 80 engage with the outside portions of the uprights 5 and 7, while the members 25 and 26 engage with the outside portions of the upright portions 6 and 8. It will, therefore, be seen that the frame 13 is prevented from 85 any transverse movement by engagement with the uprights 5, 6, 7 and 8, and is prevented from endwise movement by the engagement of the members 23, 24, 25 and 26 with the members 5, 6, 7 and 8. The frame 90 13 is, however, free to move up and down, guided by its engagement with the various members which have previously been mentioned.

There are transversely extending shafts 95 28 and 29, which are located at opposite ends of the machine, and each shaft is supported upon the main frame of the machine in any desired manner, as for instance in the case of the shaft 28, by brackets 30 and 31, which 100 are secured to the upright members 7 and 8, and in the case of the shaft 29 by brackets 32 and 33 which are secured to the upright members 5 and 6.

A lever 34 intermediate the ends bears 105 upon the shaft 28, and at its outer end has

pivots secured thereto a weight 35. At its inner end the lever is pivotally secured to an arm 36, which at its lower end is provided with a hook which engages with the 5 transversely extending brace 19. Similarly, at the opposite end of the machine there is a lever 37, which intermediate its ends, bears upon the shaft 29. This lever 37 is at its outer end pivotally secured to a weight 38, 10 and the lever is at its inner end pivotally secured to an arm 39, which at its lower end is provided with a hook that engages with the transversely extending brace 21. In the structure just described the weights 35 and 15 38 are to be of such weight that they will little more than counterbalance the frame 13, so that under the action of the weights 35 and 38 the tendency of the frame 13 will be to assume the highest position with respect to 20 the main frame, of which it is capable.

Upon the shaft 28 there is a pair of spaced cams 39 and 40. These cams are of the general shape shown in Fig. 8. Coöperating with cam 39 is a lever 41, and coöperating 25 with cam 40 is a lever 42. Each of these levers is provided with a roller upon the end to reduce the friction due to the engagement between the cam and the aforesaid lever. Levers 41 and 42 are adjustably mounted 30 upon a transversely extending shaft 43, which shaft extends transversely of the frame 13. The ends of the shaft extend through the slots 44 and 45, which are formed in the end members 24 and 25 of the 35 frame 13.

A lever 46 is at one end pivoted upon a supporting link 47, which link 47 is pivotally mounted upon the end member 25 of the frame 13. The lever 46 engages with 40 the under side of the shaft 43, and upon the movement of the lever 46 the shaft 43 is permitted to have a limited amount of movement in the slot 44. The free end of the lever 46 is by means of the spring 48 connected with an overhanging portion of the auxiliary frame.

The shaft 43 near its opposite ends is engaged upon the under portion thereof by a lever 49. This lever is at one end supported 50 by a link 50, the link 50 and the arm 49 being pivotally secured together. The link 50 is pivotally hung from one of the side members 24 of the frame 13. The lever 49 at its free end is by means of a spring 51 secured 55 to an overhanging portion of the frame 13. From the foregoing it will be seen that the shaft 55 will normally be held at the upper ends of the slots 44 and 45, because of the fact that the springs 48 and 51 will normally 60 hold the levers 46 and 49 in such position as to effect this result. However it will be apparent that flexibility and non-rigidity are secured, so that when the cams 39 and 40 push down the lever 42 and its mated lever 65 upon the opposite side of the frame the shaft

43 may be pushed down against the action of the springs 48 and 51, if the presser roller frame 13 is for any reason held against downward movement.

The shaft 29 is provided with a pair of 70 spaced cams 52 and 53, which are similar in all respects to the cams 39 and 40. These cams engage with the ends of upright levers, one of which is shown at 54, which levers are adjustably carried upon the shaft 55, that is 75 mounted in slots in side members 26 of the frame 13 in the same manner as described in respect to the shaft 43. Further, the non-rigid mounting of the shaft 55 is similar in all respects with the mounting of the 80 shaft 43.

The shaft 29 is provided near one end with a ratchet wheel 56, which is secured upon the shaft 29. This ratchet wheel is engaged by a pawl 57, which at its lower end is pivotally 85 secured upon a lever 58. The lever at some point between its ends is supported upon, but not secured to, the shaft 29, this mounting being merely a convenient mounting with respect to the operating mechanism. There 90 is a spring 59, which is at its opposite ends secured to the pawl 57 and to the lever 58, so that the pawl is normally held against the ratchet 56. The upper end of the lever 58 lies in the path of movement of outwardly extending pins 60 and 61, carried upon an annular member 62 mounted upon a shaft 63 which forms the driving shaft for the machine, and which may receive its power in any desired manner and from any desired 100 source. As the member 62 is turned, the pins 60 and 61 will alternately engage with the lever 58, partially turning the same and causing the pawl 57 to operate the ratchet 56. The amount of movement of the lever 58 is 105 such that with each engagement of a pin upon the member 62, the lever 58 will cause the pawl 57 to move the ratchet the distance of one tooth.

Upon the shaft 28 there is also a ratchet 110 wheel 63^a. This ratchet wheel is engaged by a pawl 64, which at its end is pivoted to a lever 65. The lever 65 is for convenience mounted upon the shaft 28, but has no connection with the shaft, the shaft merely 115 serving as a pivoted support for the lever 65. The lever 65 has a hub 65^a extending therefrom, and to the hub there is secured a post 66, which supports an overhanging weight 67. The weight 67 is merely for the purpose 120 of returning the pawl 64 to its original position after it has been moved forward in operating the machine. A bar or rod 68 is at one end secured to the lever 65, and at its opposite end secured to the lever 58 near the 125 lower end thereof. This rod 68 by connecting the levers 58 and 65 provides for the simultaneous operation of these levers, and consequently the simultaneous operation of the pawls 57 and 64.

The cams 39 and 40 and 52 and 53 are mounted upon their respective shafts to move in opposite directions, but the arrangement is such that similar portions of each of the cams are simultaneously engaging with the upright arms 41, 42, 54 and the companion arm to the arm 54, so that as the cams are revolved they will push down equally upon the arms with which they co-operate, and so cause the ends of the frame 13 to move downwardly equal amounts.

A presser roller 69 is mounted upon a transversely extending shaft 70. This shaft supports rollers 71 and 72, which are free to turn and are located upon opposite sides of the presser roller 69. The rollers 71 and 72 are of such diameter as to fit between the transversely extending members 14 and 15, 16 and 17 of the presser roller frame 13, and there is upon each roller 71 and 72 an inner flange which engages with the inner part of the members 14, 15, 16 and 17. It will be apparent that the members 14, 15, 16 and 17 form guides or tracks upon which the rollers 71 and 72 may roll as the presser member moves back and forth along the frame 13.

Upon the outer ends of the shaft 70 there are grooved pulleys 73 and 74. Around the pulley 73 there extends a cable 75, one end of which is secured to the extended end of shaft 43, while the opposite end of the cable is secured to the extending end of the shaft 55. The cable at its central point is secured to the pulley 73.

The grooved pulley 74 co-operates with a cable which is arranged in the same manner as cable 75.

Upon the brackets 31 and 33 there are mounted grooved pulleys 77 and 78. These pulleys are simply idler pulleys. Extending transversely of the main frame of the machine is a shaft 79. This shaft is mounted in suitable bearings which are carried by the upper longitudinally extending members 3 and 4 of the main frame. The shaft 79 extends beyond the members 3 and 4, and upon the outer overhanging portions there are mounted grooved pulleys 80 and 81.

The pulley 80 is adapted to receive an endless cable 82, which is wound several times around the pulley 80, and then is caused to pass around the idler pulleys 77 and 78, then several times around the grooved pulley 73. The cable 82 at a point substantially midway of the portion of the cable between idler pulleys 77 and 78 is secured to pulley 80, and at a similar point is also secured to pulley 73.

It will be seen that the cable 75 is wound around upon the pulley 73 so as to extend from the lower portion of the pulley 73, while the cable 82 is so wound that it engages the upper portion of the pulley 73 and extends in opposite directions.

The cable arrangement is such that as the

shaft 79 is operated, it will cause the presser roller 69 to be moved from one end of the frame 13 to the opposite end thereof.

The shaft 79 is caused to turn first in one direction and then in the opposite direction, and the time of the reversal of turning of the shaft 79 corresponds with the excursions of the presser roller 69 from end to end of the frame 13.

The mechanism for operating the shaft 79 is as follows:

The annular member 62 has secured thereto one end of a lever 84, the opposite end of which is free to reciprocate. The lever 84 is supported between its free end and its pivoted end, and for the purpose I have provided a grooved portion 85 in a drum 86 which is secured upon the shaft 79. The lever 84 has no connection with the drum 86 or with the shaft 79. It is merely supported and guided in the grooved portion 85.

Upon the lever 84 adjacent the pivoted end is a post 87, to which is secured one end of a cable 88. The cable is wound a few times around a drum 86, and the free end of the cable is fastened to a post 89. This cable is at substantially its middle portion secured to the drum 86. It will be apparent that the construction just described will reciprocate as the member 62 is turned against the lever 84, thereby alternately pulling upon the opposite ends of cable 88. When one end of the cable 88 is pulled, the drum 86 is caused to turn in a clockwise direction, while, when the opposite end of cable 88 is pulled the drum 86 will be caused to be turned in a counterclockwise direction. This then produces an alternate rotation of the shaft 79 first in one direction and then in the opposite direction.

The whole arrangement as to the reciprocation of the lever 84, the cable connecting this lever with the drum 86, and the cable connecting the grooved pulley 80 with the grooved pulley 73 are such that the presser roller 69 is caused to make alternate excursions to the opposite ends of the presser frame 13.

The grooved pulley 81 is connected to a cable which passes over idlers and connects with the grooved pulley 74 in exactly the same manner as that which has been described with respect to the pulleys 80 and 73, so that as the shaft 79 is caused to turn, the forces causing the rotation of the shaft 79, upon which the presser roller is mounted, are applied to both ends of the shaft 70 in equal degree, and thus prevent any twisting of the presser roller shaft.

Transversely of the cross member 1 and 2 of the frame, there extend tracks 90 upon which there rolls a carrier or carriage 91 having a base 91^a adapted to receive and support a pattern plate. The carriage 91 is mounted upon the wheels 92. As will be

apparent, the tracks extend outwardly from the machine, so that the carriage carrying the flask (and pattern) may be rolled under and from beneath the frame which carries 5 the presser roller.

Upon the platform 91^a there is a flask 93, and for the purpose of holding the flask there may be pins 94^b extending into suitable openings formed in the flask 93.

10 At the rear portion of the platform 91^a there are upwardly extending brackets 94 (see Fig. 5), each of which brackets at their upper ends are provided with a slot 94^a. A false flask 95 is provided which fits the flask 93. This false flask has rearwardly extending ears 96, in which are secured pins 97 that extend into the slots 94^a. The false flask, as will be readily seen, rests upon the flask 93, and permits sand to be heaped up within 20 the flask.

Extending transversely of the flask 93, I have shown braces 98. These braces may not be used in all types of flasks, but for certain types of work such as radiator molding, which employ a wide and comparatively shallow flask, it is necessary to brace the sides of the flask to keep them in alinement.

The roller 69 is provided with a transversely extending groove 69^a, and the arrangement with respect to the peripheral length of the roller and the length of the flask is such that the corner of the groove 69^a, as shown in Fig. 2, will be in position to just clear the end of the false flask to 30 which it is adjacent. As the presser roller 69 makes a movement from one side of the machine to the other, the surface of the roller will engage the sand in the flask and press it down in a manner later to be explained. When the roller has reached the end of its pressing excursion, the corner of 40 the groove 69^a, which is toward the right hand of the drawing, as shown in Fig. 2, will be adjacent what is the left hand portion of the false flask, as shown in Fig. 2. In other words the groove 69^a will accommodate the ends of the false flask so that as the presser roller rolls back and forth, and is lowered into the flask the groove 69^a will always 45 register with one or the other of the ends of the false flask when the presser roller is in its extreme right or left position.

For the purpose of accommodating the cross braces 98 in the flask 93, there are provided other grooves, 69^b, these being correctly positioned upon the roller 69, so that these grooves will straddle the braces 98 as the presser roller rolls from one end of the frame to the other. As the cams which 55 are carried by the shafts 28 and 29 are turned, the rollers carried at the ends of the levers which engage with these cams will be turned, the rollers carried at the ends of the levers which engage with these cams will be 60 pressed down.

The particular curvature imparted to the 65 cams which are carried by the shafts 28 and

29 will be determined in accordance with the distances which it is desired to lower the presser roller for successive operations thereof. In the machine which is herein described the cams have been arranged, as 70 will be seen from Fig. 8 to lower the presser roller from its normal or high position indicated at 40^a in Fig. 8, to succeeding lower positions represented at 40^b, 40^c, 40^d and 40^e, that is to say, the cam in its normal position, 75 as shown in Fig. 2, is engaging the levers at the part represented at 40^a. When the shaft has been turned the distance of one tooth of the ratchet wheels 56 and 63, the rollers of the levers which engage the cams 80 will engage with the portion marked 40^b, and so at the next movement of the ratchet wheels, with the portion of the cam 40^c, and so on throughout the surface of the cam. It 85 will be evident that the distances of the surfaces 40^b, 40^c, etc., from the center of the cam will determine just how much the presser roller will be lowered at each step in pressing the sand in the flask. It is usually preferable to move the roller in the 90 first instance its greatest distance, and to make the subsequent movements of the roller into the flask less in amount, as the same becomes compact.

The timing of the operating parts of the 95 machine is such that the frame 13 is lowered just after the presser roller passes from contact with the sand in the flask at the end of one pressing excursion of the roller and just prior to the commencement of a succeeding rolling action of the presser roller 69. It will be evident from the formation of the cam that when the cam has made a complete revolution the frame 13 will be returned to its uppermost position under 100 the influence of the weights 35 and 38.

In Fig. 2 the frame 13 appears in its highest position; in Fig. 6 the frame 13 is shown in its first lowered position from which it will be seen that the roller 69 is about to engage the sand in the false flask; in Fig. 7 there is shown the frame 13 in its lowermost position, and the presser roller in position to begin its pressing action. The intermediate positions of the frame 13 are not shown 110 in the drawings, but it will be understood that the frame assumes intermediate positions as the cams carried by the shafts 28 and 29 are rotated.

In the drawing, more particularly in Fig. 1, I have shown stops 100, which limit the movement of the mold carrying car 91, and properly position it beneath the presser roller 69. If desired, these may be omitted or otherwise disposed, and the tracks extending from both sides of the frame of the machine be left open so that a car carrying a flask may be moved beneath the machine from one side, while a car is being removed from beneath the presser roller on the other 120 125 130

side, thus providing for continuous operation of the machine.

In Fig. 9 there is shown an arrangement of elements, which will automatically raise the sprue former as the car 91 with its mold is moved from beneath the presser roller.

Near the end of the flask there is an opening through the platform 91^a which accommodates the downwardly extending rod 101 of a sprue former 102. The car carries a guide 103 which guides the lower end of the sprue former.

Pivoted upon one of the lower side members of the frame of the molding machine 15 is a lever generally represented at 104. This lever is pivoted, as indicated at 105, a portion of the lever extending transversely of the machine, and another portion of the lever extending outside of and beyond the 20 machine. The portion of the lever 104, which is outside of the machine, is formed with a slanting surface 104^a and with a straight surface 104^b near the end. The lever 104 is free to swing on its pivot in one 25 direction, but the outer end of the lever 104 is adapted to engage a stop 106, as indicated in Fig. 9.

When the sprue former 102 is inserted in the flask and the car and flask are in the 30 position shown at the right end of Fig. 9, sand will be dumped into the flask which will surround the sprue former and hold it in position. When the car and flask are in the position shown in dotted lines in 35 Fig. 9, and the presser roller presses the sand in the flask, the sprue former will be shoved downwardly as the presser roller is lowered into the flask; that portion of the lever 104 with which the sprue former may 40 engage is free to move so that the sprue former may move down as far as it may be pushed by the presser roller. When, after the sand in the flask is pressed, the car is moved outwardly from beneath the 45 present roller, the sprue former will engage with the inclined portion of the lever 104, thereby causing the sprue former to be pushed up and permitting its ready removal from the sand in the flask.

50 It is desirable that machines of the character herein shown shall work along the molding floor as the sand is used to make molds, in order that the machine shall follow the pile of sand rather than that sand be brought to the machine. To accomplish this result, the machine is constructed so that as the machine is operated it will propel itself by slow degrees along the floor.

In carrying out this provision, I provide 60 on one or more of the wheels upon which the frame is mounted a ratchet wheel 107. Upon the shaft which carries the wheel and ratchet wheel, a bell crank 108 may be mounted at the central portion thereof. One 65 arm of the bell crank carries a pawl 109

which engages with the teeth of the ratchet wheel 107. The other arm of the bell crank lever is pivotally connected with a rod 110, and this rod is eccentrically mounted upon a disk 111, carried upon the cam shaft 29. 70 As the cam shaft is turned by the ratchet carried thereby, it will cause the ratchet wheel 107 to be turned, thereby to cause the wheel axle which carries the cam to turn and so propel the whole machine, and obviously the arrangement may be such as to cause the machine to be advanced as rapidly 75 or as slowly as desired.

It is believed that the operation of the machine will be obvious from the foregoing 80 description. However, a brief description of the functioning of the machine during the making of a mold will be described.

The first position of the carriage 91 and the flask carried thereby, is that shown at 85 the right hand of Fig. 9, it being understood that there is a pattern secured to the platform 91^a of the car 91. Sand is shoveled into the flask and fills the flask and false flask. The car 91 is then pushed on its 90 tracks so as to come beneath the presser roller. At this time the frame 13 and the presser roller 69 are in their highest positions, as shown in Figs. 1 and 2. As the shaft 63 is turned it first causes the cams 95 carried by the shafts 28 and 29 to turn to the position shown in Fig. 6, that is to say, the presser roller is lowered so as to be in a position to compact the sand within the false flask. As soon as the presser roller is 100 lowered, the presser roller begins to turn in a counterclockwise direction and travels across the frame 13, pressing the sand as it travels. When the presser roller has reached its position at the opposite end of 105 the frame 13 to that shown in Fig. 2, the cams upon the shaft 28 and 29 are again moved, thus lowering the frame and thereupon the presser roller 69 is again caused to roll, this time in a clockwise direction to that end of 110 the frame in which it is shown in Fig. 2.

The frame 13 is successively lowered under the action of the cams carried upon the shafts 28 and 29 until in the position shown in Fig. 7, which is the lowermost 115 position and the mold is pressed in each position. When the roller 69 rolls the sand in the flask, while the frame 13 is in the position shown in Fig. 7, the rolling of the mold will be completed, and the next movement by the mechanism of the machine will be to turn the cams carried by the shafts 28 and 29 into the position shown in Fig. 2, which permits the frame 13 to be elevated, 120 due to the counterweights 35 and 38.

The car 91 will then be moved into the position shown at the right hand of Fig. 9, which will cause the sprue former to be elevated.

The shafts 45 and 55 upon which the 130

levers coöperating with the cams carried by the shafts 28 and 29 are mounted, are, as will be remembered from the construction heretofore described, flexibly mounted and held by the levers 46, 47, 48 and 49. If during the operation of the presser roller, the sand does not readily give and compact beneath the presser roller, so that the frame 13 cannot be moved downward by the action 10 of the cams carried by the shafts 28 and 29, the shafts 45 and 55 will cause the levers 46 and 47, 48 and 49 to be moved against the action of the springs engaging the outer ends of these levers. The construction just 15 described affords a flexible connection, so that no damage will be done to the machine.

It will be obvious that various changes may be made in the precise construction described in this specification without departing from the spirit of the invention.

Having thus described my invention, what I claim is:—

1. In a molding machine, the combination with a device adapted to support a flask, of a 25 presser element adapted to successively engage the sand in different portions of the flask, and means for progressively moving the said presser element toward the flask after each such engagement.

2. In a molding machine, the combination with a device adapted to support a flask, a presser roller adapted to progressively engage different portions of the sand in the flask, and means for moving said presser 35 roller progressively and intermittently toward the flask after each such engagement.

3. A molding machine, comprising a device adapted to support a flask, a presser roller, means for causing said presser roller 40 to move progressively across the flask, and means for moving the presser roller in intermittent steps toward the flask.

4. In a molding machine, the combination with a device for supporting the flask, of a 45 movable guiding frame, a presser member supported by said guiding frame, means for moving the presser member progressively across the flask, and means for intermittently lowering the frame and presser member toward the flask.

5. In a molding machine, the combination with a device for supporting a flask, of a 55 presser member, means for moving said presser member progressively across the flask and in contact with the sand therein, and means for moving the presser member toward the flask, said last mentioned means being operated at the end of each excursion of the presser member across the flask.

6. In a molding machine, the combination with a device for supporting the flask, a 60 guiding frame above the flask, a presser member carried by the said frame, means for moving the presser member along the guiding frame and across the flask in con-

tact with the sand therein, and means for moving the said frame toward the flask at the end of an excursion of the presser member across the flask.

7. In a molding machine, the combination 70 with a device for supporting the flask, of a guiding frame above the flask, a presser member, means for moving said presser member to and fro in the said frame, said presser member moving across the flask and 75 engaging the sand therein upon each excursion, and means for moving the frame and presser roller toward the flask at the end of each excursion of the presser member.

8. In a molding machine, the combination 80 with a device for supporting the flask, of a guiding frame supported above the flask, a presser roller guided by the said frame, means for turning said presser roller, thereby to cause it to make excursions to and fro 85 in the guiding frame, the presser roller engaging the sand within the flask upon each excursion, and means for moving the guiding frame and presser roller toward the flask at the end of each excursion of the presser 90 roller.

9. In a molding machine, the combination with a main frame, of an auxiliary frame mounted within the main frame, a presser member supported in the auxiliary frame, 95 means for causing the presser member to move to and fro in the said frame to engage the sand within the flask, and means for causing the auxiliary frame to be moved toward the flask at the end of each excursion 100 of the presser member.

10. In a molding machine, the combination with a main frame, of an auxiliary frame 105 slidably mounted within the main frame, a presser roller carried by the auxiliary frame, means for causing the presser roller to turn and make excursions from end to end of the auxiliary frame, mechanism causing the auxiliary frame to be intermittently moved toward the flask, said mechanism being operative at the time the presser roller is at the end of an excursion.

11. In a molding machine, the combination with a main frame, of an auxiliary frame 115 slidably mounted within the main frame, a presser roller carried by the said auxiliary frame, means for causing the presser roller to turn and make excursions from end to end of the machine, mechanism including cams which are intermittently moved to cause the auxiliary frame to be lowered toward the flask, said movement of the cams occurring at the time that the presser roller is at the end of the excursion.

12. In a molding machine, the combination with a main frame, an auxiliary frame 125 slidably mounted within the main frame, a presser roller mounted in the auxiliary frame, means for causing the presser roller to turn and make excursions from end to 130

end of the auxiliary frame, shafts mounted adjacent each end of the main frame, cams carried by the said shaft, arms carried by the auxiliary frame which engage with the 5 said cams, means for intermittently moving said cam shafts, the said movement of the cam shafts occurring at a time when the presser roller is at the end of an excursion.

13. In a molding machine, the combination 10 with a main frame, of an auxiliary frame slidably mounted in the main frame, a presser roller carried by the auxiliary frame, shafts mounted at each end of the main frame, cams carried by the said shafts, 15 arms carried by the auxiliary frame adapted to engage with the cams, said arms being yieldingly mounted upon the auxiliary frame, mechanism for intermittently turning the cams, said mechanism being operative 20 at the end of an excursion of the presser roller.

14. In a molding machine, the combination 25 with a main frame, of an auxiliary frame slidably mounted in the main frame, means for causing said auxiliary frame to normally lie at the upper portion of the main frame, a presser roller carried by the auxiliary frame, means for causing said presser roller to turn and to make excursions 30 to and fro in the auxiliary frame, cams carried by the main frame, means upon the auxiliary frame which engage with the cams on the main frame, means for intermittently turning 35 said cams, whereby the auxiliary frame is intermittently lowered toward the flask, said movement of the cams occurring when the presser roller is at the end of an excursion.

15. In a molding machine, the combination 40 with a main frame, of an auxiliary frame slidably mounted in the frame, shafts mounted at the opposite ends of the main frame, cams carried by the said shafts, arms carried by the auxiliary frame and engaging 45 the cams, ratchets carried by the shafts upon which the cams are mounted, pawls engaging said ratchets, means connecting the said pawls whereby they operate simultaneously, and means for operating the said 50 pawls.

16. In a molding machine, the combination 55 with a main frame, of an auxiliary frame slidably mounted in the main frame, a presser roller mounted in the auxiliary frame, grooved pulleys associated with the opposite ends of the presser roller, cables associated with the said grooved pulleys on the presser roller, and means for moving the cables to cause the presser roller to roll from 60 end to end of the said auxiliary frame.

17. In a molding machine, the combination 65 with a main frame, of an auxiliary frame slidably mounted within the main frame, a presser roller mounted in the auxiliary frame, said auxiliary frame forming

a guide for the presser roller, grooved pulleys associated with the presser roller at opposite ends thereof, grooved pulleys mounted at the upper portion of the main frame, cable connections between the grooved 70 pulleys on the main frame and the grooved pulleys on the presser roller, means for turning the grooved pulleys on the main frame alternately in opposite directions whereby the presser roller is caused to make excursions by rolling from end to end of the auxiliary frame.

18. In a molding machine, the combination 75 with a main frame, an auxiliary frame, a presser roller mounted in the auxiliary frame and adapted to be guided by the said frame, grooved pulleys associated with the presser roller at the opposite ends thereof, grooved pulleys carried by the main frame 80 cable connections between the grooved pulleys on the frame, and grooved pulleys on the presser roller, a power shaft, a crank associated with the power shaft, a reciprocating arm pivotally connected with the crank and operative connections between 85 said reciprocating arm and the grooved pulleys carried by the main frame whereby the grooved pulleys on the frame are rotated first in one direction and then in the opposite direction whereby the presser 90 roller is turned and caused to make excursions while rolling from one end of the frame to the other.

19. In a molding machine, the combination 95 with a main frame, of an auxiliary 100 frame slidably mounted in the main frame, a presser roller carried by the auxiliary frame, grooved pulleys carried by the presser roller adjacent opposite ends thereof, a shaft mounted at the upper portion of the 105 main frame, grooved pulleys carried by said shaft, connections between the grooved pulleys upon the presser roller and the grooved pulleys upon the main frame, a power shaft, a crank carried by the power shaft, a reciprocating arm pivotally mounted upon the 110 crank, a drum carried by the shaft upon which the grooved pulleys upon the main frame are mounted, a cable wound upon said drum and secured at opposite ends of the 115 reciprocating arm, and means for turning the power shaft.

20. In a molding machine the combination 120 with a main frame of an auxiliary frame slidably mounted in the main frame, a presser roller carried by the auxiliary frame, means for moving said presser roller transversely of the auxiliary frame, grooved pulleys carried at the outer end portions of the presser roller, a stationary cable coöperating 125 with each of said grooved pulleys whereby the presser roller is kept in alignment as it moves transversely of the auxiliary frame.

21. In a molding machine the combina- 130

tion with a main frame of an auxiliary frame slidably mounted in the main frame, a presser roller supported by the auxiliary frame and adapted to move transversely of 5 said auxiliary frame, a grooved pulley adjacent each end of the presser roller, a stationary cable coöperating with each of said grooved pulleys to keep the presser roller in alinement as it moves across the frame, 10 a movable cable associated with each of said grooved pulleys, the movement of the last mentioned cable causing the presser roller to move transversely of the frame.

22. In a molding machine the combination 15 with a main frame of an auxiliary frame carried by the main frame and slidably mounted therein, a compressor member carried by the auxiliary frame and movable in said auxiliary frame, means for resiliently 20 holding the auxiliary frame normally at the upper portion of the main frame and means for moving the auxiliary frame against the action of the means which holds the auxiliary frame toward the upper end of the main 25 frame.

23. In a molding machine the combination with a main frame of an auxiliary frame slidably mounted in the main frame, a presser member carried by the auxiliary 30 frame and movable in said auxiliary frame, means normally tending to move the auxiliary frame toward the upper part of the main frame, and means for moving the auxiliary frame away from the upper portion of 35 the main frame in intermittent steps.

24. In a molding machine the combination of a main frame of an auxiliary frame slidably mounted in the main frame, weights connected with the auxiliary frame whereby 40 the auxiliary frame is normally urged to a position at the upper portion of the main frame, cams carried by the main frame, means upon the auxiliary frame with which the cams coöperate and means for intermittently 45 operating said cams, thereby to move the auxiliary frame by steps against the action of the weights.

25. In a molding machine the combination with a main frame of an auxiliary frame 50 slidably mounted in the main frame, means for normally urging the auxiliary frame toward the upper portion of the main frame, cams carried by the main frame, means upon the auxiliary frame coöperating with said 55 cams, a ratchet mechanism associated with said cams, and means for intermittently operating said ratchet mechanism whereby the auxiliary frame is moved in the main frame.

26. In a molding machine the combination 60 with a main frame of an auxiliary frame slidably mounted in the main frame, means for normally urging the auxiliary frame toward the upper part of the main frame, cams carried by the main frame, means upon 65 the auxiliary frame coöperating with the

said cams, ratchet mechanism associated with the cams, a lever for operating the ratchet mechanism, a rotatable member carried by the main frame, means for applying power to said rotatable member, said rotatable member being provided with projections adapted to alternately engage the lever for operating the ratchet mechanism whereby the auxiliary frame is moved step by step in the main frame. 70 75

27. In a molding machine the combination with a main frame of an auxiliary frame slidably mounted in the main frame, a presser roller carried by the said auxiliary frame and adapted to make excursions back and forth transversely of the auxiliary frame, 80 means for normally urging the auxiliary frame toward the upper part of the main frame, means for moving said auxiliary frame intermittently away from the upper portion of the main frame, means for causing the presser roller to move in the auxiliary frame, and operating means operatively connected with the means which causes the presser roller to move and also operatively 85 connected with the means which causes the auxiliary frame to intermittently move in the main frame.

28. In a molding machine the combination with the main frame of an auxiliary frame 90 slidably mounted in the main frame, means normally urging the auxiliary frame toward the upper portion of the main frame, a presser roller adapted to make excursions back and forth transversely of the auxiliary 95 frame, cams carried by the main frame, means coöperating with the cams carried by the auxiliary frame, a ratchet mechanism co-operating with the cams, means for causing the presser roller to turn, a power shaft, an 100 operating element carried by the power shaft, operative connections between said operating element, and a means which causes the presser roller to turn, and operative connections between the operating element and 105 the ratchet mechanism whereby the ratchet mechanism is caused to operate. 110

29. In a molding machine the combination with a main frame, an auxiliary frame slidably mounted in said main frame, a movable flask-carrying means adapted to be placed in the main frame beneath the auxiliary frame, a sprue former slidably mounted in the flask, means carried by the frame for engaging the sprue former as the flask is moved from beneath the auxiliary frame, thereby 115 to raise the sprue former. 120

30. In a molding machine the combination with a main frame, means carried by the main frame for pressing sand in a flask, a 125 movable carriage adapted to move upon the main frame beneath the sand compressing means, a sprue former slidably supported upon the said carriage, and means carried by the main frame for causing the sprue 130

former to be elevated as the carriage is moved from beneath the said pressing element in the main frame.

31. In a molding machine the combination 5 with a movable carriage adapted to support a flask of a relatively stationary pressing means adapted to press the sand within the flask, a sprue former slidably supported by the said movable carriage, and means adapted to engage said sprue former to elevate the same as the carriage is moved from beneath the sand pressing means.

32. In a molding machine the combination 15 with a stationary sand pressing means of a movable carriage adapted to coöperate with the sand pressing means, and to support a flask, a slidable sprue former mounted upon said carriage and extending beneath the carriage, and a member with which the sprue former contacts to elevate the same as the carriage is moved from beneath the sand pressing means.

33. In a molding machine the combination 25 with a frame, a sand pressing means supported by the frame, a movable carriage adapted to coöperate with the sand pressing means, tracks for guiding the said carriage, a slidable sprue former carried by the carriage and extending beneath the carriage, and means carried by said frame adapted to engage the lower end of the sprue former to elevate the same as the carriage is moved from beneath the sand pressing element.

34. In a molding machine, the combination 35 with a device for supporting a flask, of a presser member for pressing sand in the flask, means causing the presser member to press the sand in the flask, and means for causing intermittent relative movement between the presser member and flask whereby the presser member is caused to approach the flask after each operation of the presser member.

35. In a molding machine, the combination 45 with a flask supporting member, a presser member adapted to progressively engage different portions of the sand in the flask, and means for causing intermittent relative movement between said members, so as to cause one of said members to gradually approach the other after each engagement of the presser member above specified.

36. In a molding machine, the combination 55 with a presser member adapted to progressively engage different portions of the sand in a flask, and means for intermittently lowering the presser member.

37. In a molding machine, a flask supporting member, a presser roller, means for causing said roller to move back and forth on the sand in the flask, and means for causing the flask supporting member and roller to gradually approach each other by moving one of said members intermittently toward 65 the other.

38. In a molding machine, the combination with a flask supporting member, a presser member, a guide frame supporting said presser member, means for shifting said presser member back and forth across the 70 guide frame, and means for causing the flask supporting member and guide frame to approach each other by moving one of the same intermittently relative to the other.

39. In a molding machine, a flask supporting member, a presser member adapted to be moved back and forth across the flask, and means for causing the presser member and flask supporting member to approach each other by shifting one of said members 80 toward the other when the presser member is at one end of its movement across the flask.

40. In a molding machine, a flask supporting member, a guide frame for a presser 85 member adapted to compress sand in the flask, a presser member movable back and forth in said guide frame, and means for causing said guide frame and flask supporting member to approach each other by moving one of the same toward the other when the presser member is at one end of its movement in the guide frame.

41. In a molding machine, a main frame, a relatively movable auxiliary frame carried 95 by the main frame, means normally holding the auxiliary frame at its upper position in the main frame, a presser member carried by said auxiliary frame, means for moving said presser member relative to the 100 same frame, and means for moving the auxiliary frame against the action of the means which normally tend to hold the same in its upper position.

42. In a molding machine, a frame, a 105 presser member adapted to compress sand in a flask, a support for said presser member, means for causing intermittent relative movement between the frame and said support, said means comprising a plurality of 110 members carried by one of said elements, a plurality of members carried by the other of said elements and coöperating with the first named elements, and means for moving the presser member in contact with the sand 115 in different parts of the flask between each said intermittent movement.

43. In a molding machine, a main frame, an auxiliary frame mounted in the main frame, a presser member carried by the auxiliary frame, means for intermittently lowering the auxiliary frame in the main frame, said means comprising cams carried by one of said frames, means carried by the other of said frames and coöperating with the 120 same, and means for moving the presser member in contact with the sand in different parts of the flask between each said intermittent movement.

44. In a molding machine, a main frame, 130

an auxiliary frame mounted in the main frame, a presser member carried by the auxiliary frame and adapted to compress sand in a flask, means for intermittently lowering said auxiliary frame, comprising cams carried by one of said frames, means carried by the other of said frames and coöperating with the cams, means for intermittently turning said cams, and means for moving the presser member into contact with sand in different parts of the flask between each said intermittent movement.

45. In a molding machine, a frame, a movable flask carrying member adapted to be moved under the frame, a sprue former slidably mounted in the flask, and means carried by the frame for engaging the sprue former as said member is moved from beneath the frame whereby the sprue former will be elevated.

46. In a molding machine, a sand pressing device, means for supporting and forming the bottom of a flask beneath the pressing

device, a flask supported by said means said flask having an opening formed in the means forming the bottom thereof, a sprue former mounted in said opening and slidable therein and adapted to be pressed down as the pressing device descends into the flask.

47. In a molding machine, a main frame having means for supporting a flask, an auxiliary frame in the main frame and movable relative thereto, a presser member carried by the auxiliary frame, means for lowering the auxiliary frame, and yieldable means for rendering the lowering means ineffective when predetermined resistance to movement is encountered.

In testimony whereof, I hereunto affix my signature in the presence of two witnesses.

JAMES POWELL,
Administrator of Jesse A. Field, deceased.
